DES. 2062

John Rogers, of New York, N.Y.

Letters Patent No. 1062, Dated May 9, 1865.

Design for a Group of Figures.

The schedule referred to in these Letters Patent and making part of the same:

So all where it may occur.

Be it known that I, John Rogers, of the City of New York, and County and State of New York, have invented or produced a new and original design for a group of figures; and I do hereby declare that the following is a full and exact description of the same.

The group consists of two male figures and is called "The Home Guard or Midnight on the Border." They are represented as having been suddenly aroused in the night by an alarm. The larger figure is in the act of cocking a pistol. Hanging to his left side is the smaller figure who stands peering into the darkness, as fully shown in the accompanying drawing.

Having thus described my invention, what claim and desire to secure by Letters Patent is the design for a group of statuary as herein set forth and described.
